SINGLE REED CELL BLOCK

Charles De Gasero, New Hyde Park, N. Y.

Application September 10, 1951, Serial No. 245,917

4 Claims. (Cl. 84—376)

1

My invention pertains in general to new and useful improvements in the reed and cell block structures of musical instruments of the accordion type. It is particularly concerned with an improved single reed structure and valve arrangement in association with a novel cell block.

The primary object of the invention is to replace the conventional double reed and associated cell block arrangement, and thereby eliminate the many well known disadvantages associated with double reed instruments; such as, inferior tonal qualities due to small cells, difficulties in tuning, and considerable expense in the multiplication of parts.

In my invention the reed holder or block is partitioned off into a plurality of cells or tonal chambers, in each of which is contained a plate carrying a single reed or tongue. Finger valves control the admission or escape of air from the bellows, and through a novel arrangement of valves associated with each cell a stream of air is adapted to flow over the reed in a single direction to cause it to vibrate, whether the bellows are compressed or expanded. Through novel adjusting means associated with the valves the flow of air to the reed cell can be regulated to tune or control the pitch and amplitude of the sound that may be produced, in such manner that the tone or sound emitted by the vibrating reed upon compression of the hollows is the same as that produced upon expansion of the bellows.

The reeds are secured in suitable manner within the several cells of the block. Where repairs, replacement or other adjustments are required, ready access is allowed to the reeds by a novel removable cover common to the several cells of the block.

Besides the particular arrangement of the single reed in the cell block, another novelty of the invention is the peculiar construction of the valve assemblies associated with each cell. These comprise a pair of frames for each cell in which are carried valves in the nature of hinges. The valves are of a material not given to curling or drying out, such as occurs with leather valves, and they are adapted to close without slapping noises.

Another noteworthy feature of the invention is the adjusting means whereby tuning of the reed is simplified through regulation of the volume and force of air passing through the cell or tonal chamber to vibrate the reed. This comprises suitable means such as a plate that may be adjusted to enlarge or diminish either an intake or an escape valve opening of a cell, as the case may re-

2

quire, so as to control the stream of air in or out of the cell.

A further advantage of this invention is the increased size of the cells allowed by the single reed plate, whereby better tone and musical qualities are effected. Because of the larger cell size the single reed, where desired, may be made wider to produce the deeper tones. This is not possible in the double type reed instruments, because of lack of space due to the small cells so that end weights are required on the reeds to effect the bass tones.

The general object of the invention is, therefore, an improved single reed, valve and cell block arrangement in musical instruments of the accordion type.

Another object of the invention is a single reed, valve and cell block arrangement together with adjusting means for controlling the stream of air over the reed of a cell to flow in a single direction and in such manner that the tone produced upon expansion of the bellows is the same as that produced when the bellows are compressed.

A further object of the invention is an improved cell block for accordion type instruments that is provided with a removable cover section enabling easy and ready access to the interior of the reed chambers for adjustment or replacement of the reeds.

Another object of the invention is an improved type of valve in the nature of a hinge and of a material not given to curling or drying out.

A still further, and not the last object of the invention is a novel frame for carrying the cell valves, and so constructed as to eliminate slapping noises often associated with the closing of valves.

The foregoing objects and advantages, as well as others, will become readily apparent as this specification gradually unfolds in detail and as this specification is read in conjunction with the accompanying drawings wherein a preferred form of the invention is illustrated.

In the drawings:

Fig. 1 is a side elevational view of one of the long sides of the cell block, broken away in part.

Fig. 2 is a view of the cell block opposed to that shown in Fig. 1.

Fig. 3 is a cross section of the cell block taken on the line 3—3 of Fig. 1.

Fig. 4 is a perspective view of a reed plate.

Fig. 5 is a view of the reed plate opposed to that shown in Fig. 4.

Fig. 6 is a plan view of the top frame of the cell block broken away in part.

Fig. 7 is a bottom plan view of the bottom frame of the cell block broken away in part.

Fig. 8 is a section of the accordion framing intended to show the association of the cell block with the accordion.

Fig. 9 is a detail perspective view of an enlarged scale of a frame containing the intake valves.

Fig. 10 is a vertical section taken midway of Fig. 9.

Fig. 11 is a detail perspective view on an enlarged scale of a frame containing the escape valves.

Fig. 12 is a view of a typical valve used in the valve frames of Figs. 9 and 11.

In describing the invention in detail reference is directed to the several drawings, wherein Fig. 8 there is a portion of a conventional frame end 1 or wall 1 of an accordion to which is attached a conventional bellows 2. Mounted in conventional manner on the frame end is a cell block 3 embodying my invention. The cell block comprises a pair of end walls 4 mounted upon a base member 5, and includes a top frame member 6 spanning the end walls. A successive series of thin walls 7 partition the cell block off into a series of cells generally designated 8. Each cell opens at 9 through the top frame and at 10 through the base frame.

The top openings 9 are closed over by a cover 11 which is common to the several cell top openings. The cover is secured over the cell top openings by proper means, such as latches 12 at each end of the cell block adapted to allow for ready removal of the cover from the block when required. The undersurface of the cover is provided with a suitable lining 13 of a material adequate to insure an airtight sealing of the cover over the cell top openings. Here the lining material is of soft leather.

A reed plate 14 is sealed within each cell in a suitable manner, preferably by wax 15. Wax is used for this purpose as it serves as a cushion and also allows for ready removal of the reed plate when desired. The reed plate is of light material; such as, aluminum, and it is provided with a single slot in the form of a rectangular aperture 16. On the reed plate is a free reed 18, also called a tongue, which is firmly secured at one end to the plate by a rivet 19. The free end of the reed is adapted to move or vibrate within slot 16. When at rest the reed free end is slightly above the aperture, so that a stream of air flowing over it catches and causes it to vibrate. Reed plate 14 is substantially the width of the cell and located about midway therein in a slightly inclined position.

Conventional means is provided for securing the cell block to the frame end 1 of the accordion. This means includes the extended ends 20 of the base member 5, which ends are removably securable in suitable receptacles 21, of which one is shown, on the frame end 1. The frame end is provided with suitable finger valves 22. Each finger valve here is adapted to control an opening in the frame end 1 which communicates with the base openings 10 of two adjacent cells 8 of the cell block, so arranged that opening of a finger valve will allow a flow of air into or from both cells, depending upon whether the bellows are compressed or expanded, to produce a tone from each cell. It is conventional for purposes of added volume, quality and blending of tones to have more than one reed simultaneously vibrating for each note produced.

To control a flow of air in a single direction over a reed to cause it to vibrate within its cell whether the bellows are compressed or expanded,

two sets of valves are provided for this purpose for each cell, one a set of intake valves, the other a set of escape valves.

The intake valves are carried by a frame 25, and the escape valves are carried by another frame 26. Frame 25 closes over the one end of a cell, while frame 26 closes over the opposite end of the cell. To allow for the valve frames each cell opens as at 24 through to the opposite sides of the cell block. A frame 25 carrying the intake valves is sealed in the one end of the cell by a proper material to allow for ready removal when desired; such as wax, while a frame 26 carrying the escape valves is similarly sealed in the opposite end of the cell. Intake frame 25 has an elongated wall 27 near the top of which is an aperture or slot 28 that opens into the cell. Slot 28 is controlled by a valve member 29 that opens inwardly into the cell chamber when the bellows are compressed and which is adapted to close over the slot when the bellows are expanded. Valve 29 is flat and operates as a hinge. For this effect it is provided with a pintle 30 which pivots at its ends in side frame flanges 31. Valve 29 allows an intake of air into the reed cell when the bellows are compressed.

A substantial cubical extension 32 on the inner side of the lower end of frame 25 extends into the base portion of the cell. Extension 32 is provided with front, back and side walls 33, but is open in its upper and lower ends 34. A flange 35 about the inner walls of extension 32 serves as a seat for a flat valve member 36 which is adapted to open inwardly into the cell when the bellows are expanded allowing an intake of air to the cell from an open related finger valve. Valve 36 is adapted to close upon its seat when the bellows are compressed. This valve also operates in hinge fashion, and is similarly provided with a pintle 30 which pivots at its ends in the side walls 33 of extension 32.

The escape valve frame 26 also has an elongated wall 31 near the top of which is an aperture or slot 38 that opens into the cell. Slot 38 is controlled by a flat valve member 39 located on the outside of the frame wall and which is adapted to close over slot 38 when the bellows are compressed, and to open outwardly or move away from the slot when the bellows are expanded. Valve 39 allows an escape of air from the cell into the bellows when the bellows are expanded. This valve also operates in hinge fashion and is provided with a pintle 30 which pivots at its ends in outward extensions 40 of the frame wall.

On the inner side of escape valve frame 26 at its lower end is an angular extension 41 inclined downward. Extension 41 is provided with a rectangular slot 42 about which is a marginal flange 43. Flange 43 acts as a seat for a flat valve member 45. Valve member 45 is adapted to close over slot 42 to prevent an intake of air from an open finger valve when the bellows are expanded, and to uncover the slot to allow an escape of air from the cell when the bellows are compressed.

It is to be noted that the reed plate is located in an inclined position in the cell and that the reed or tongue 18 is always on the side of the cell facing the intake valves. The reed plate divides its cell into two compartments 46, 47. The intake valves 29 and 36 control the admission of air to the compartment 46 on the reed side of the plate to vibrate the reed. The escape valves 39 and 45

control the escape of flowing air over the vibrating reed into the compartment 47 on the other side of the reed plate.

Through the foregoing arrangement a stream of air is caused to flow in a single direction over the reed within the cell to vibrate it whether the bellows are compressed or expanded.

The frames 25 and 26 are sealed about by the wax 15 in their respective end openings of a cell in such manner that air does not enter or escape 10 from the cell except by way of the valves, and the reed plate is so sealed about by wax within its cell that air does not pass from one compartment of the cell to the other except over the reed.

The manner of operation of the valves in any 15 cell of the cell block is as follows: When the bellows are expanded air is drawn through any of the finger valves that may be open. Air flowing through a finger valve 22 forces open the bottom intake valve 36 of a related cell to admit a stream of air to the reed compartment side 46 of the cell, and simultaneously closes the bottom escape valve 45 communicating with the other compartment 47 of the cell. Upon entering compartment 46 the air stream forces the side intake valve 29 shut, upon catching the reed causes it to vibrate producing a sound, and in doing so passes on over the reed to the escape compartment 47 of the cell. After passing over into the escape compartment the air escapes through the side escape valve 39 into the bellows. The pressure of the air stream in flowing over the vibrating reed is baffled and necessarily reduced, and due to the greater counter air pressure being forced against the bottom escape valve 45 from the finger valve, the air stream in escaping from the cell necessarily prefers the side escape valve 39.

Now, when the bellows are compressed and the finger valve of a particular cell is opened, a stream of air from the bellows is blown against the side escape valve 39 to close it and simultaneously is blown against the side intake valve 29 to open it and enter the reed side 46 of the cell. In entering cell compartment 46 the air forces the bottom intake valve 36 shut, vibrates and passes over the reed to the escape compartment 47 of the cell. In compartment 47 the air stream forces open the bottom escape valve 45 and escapes to the outside of the accordion through the open finger valve. Escape valve 45 is necessarily selected by the escaping air stream in preference to the side escape valve 39 due to the greater counter air pressure holding valve 39 shut.

It is to be noted that the valve seats in frames 25, 26 are slightly lipped or turned up, as at 48. This construction is desired as it serves to eliminate slapping noises of the valves when closing which would otherwise occur were the valves when closing to strike flat surfaces.

The intake and escape valves are of novel construction (Fig. 12). They are formed of material, preferably rubber, that is not given to curling or drying out, such as occurs with the leather valves conventionally used in double reed instruments. The pintles 38 are of firm material as metal, and are an integral part of the valves. They are moulded in the valve when the valve is formed.

Another feature of the invention is adjustable means to control the pitch and volume of sound produced by a cell, so that the sound produced by a cell when the bellows are expanded is the same as that emitted when the bellows are compressed. This control comprises means for regulating the size of the side intake and the side escape valves

29, 39. For this purpose each cell includes a fan plate 49 fixed to a pivot 50 above the side intake valve 29 on the outside of frame 25, and a similar fan plate 51 fixed to a pivot 52 above the side escape valve 39 on the inside of frame 26. Fan plates 49, 51 are adapted to be moved upon manually turning their respective pivots which are provided with a suitable screw-driver slot for this purpose. Moving the fan plates over their respective openings serves to diminish the size of their respective openings to the extent desired. Diminishing the size of the valve openings increases the force of the air stream within the cell to effect the volume and pitch of the sound produced. By regulating the size of either or both the side intake valve and the side escape valve of a cell an adjustment or tuning may be made until the sound produced by the bellows on expanding is the same as that produced on compressing the bellows.

Each finger valve preferably controls a pair of cells, and while the intake valve frames 25 of each cell may be located on the same side of the cell block and the escape valve frames 26 on the other, 25 it is desired that the positions of these members be reversed in one of the cells of each pair, as appears from the Figs. 1 and 2. Where this arrangement is not had illusions in the locale of the sound occur, in that the sound appears to come 30 from one part of the bellows when they are expanded and from another part when they are contracted; whereas, by having a pair of cells controlled by a single finger valve and the elements of one cell of the pair reversed in position to those of the other, the true locale of the sound 35 is obtained.

While I have described and exhibited a preferred form of my invention, it is my intent, however, to claim not only the form of the invention 40 as described, but also all forms of the invention as may be reasonably construed to be within the spirit of the invention and within the scope of the appended claims.

I claim:

1. In an accordion including bellows, a cell block comprising a plurality of cells one adjacent the other and each the full width of the cell block, a reed plate carrying a single free reed within each cell, an individual frame member removably sealed in one side of each cell carrying a pair of air intake valves, and another individual frame member removably sealed in the opposite side of each cell carrying a pair of air escape valves, so constructed and arranged 45 whereby when the bellows are expanded air is drawn into a cell through one of the intake valves and in vibrating the free reed escapes from the cell into the bellows through one of the escape valves, and when the bellows are compressed air is forced into the cell through the other of the intake valves and in vibrating the free reed escapes from the cell through the other of the escape valves, an air-tight cover common 50 to the several cells of the block, and latching means whereby the cover may be readily removed, the reed plate and interior of each cell 55 being exposed upon removal of the cover.

2. In an accordion including bellows, a cell block comprising a plurality of cells one adjacent the other and each the full width of the cell block, a reed plate carrying a single free reed within each cell, an individual frame member removably sealed in one side of each cell carrying a pair of air intake valves, and another 60 individual frame member removably sealed in the

opposite side of each cell carrying a pair of air escape valves, so constructed and arranged whereby when the bellows are expanded air is drawn into a cell through one of the intake valves and in vibrating the free reed escapes from the cell into the bellows through one of the escape valves, and when the bellows are compressed air is forced into the cell through the other of the intake valves and in vibrating the free reed escapes from the cell through the other of the escape valves, a base frame member, a pair of end walls mounted upon the base frame member, a top frame member spanning the end walls and including a series of openings registering with each cell of the block, an airtight cover common to the several openings of the top frame member, and latching means removably securing the cover over the top frame member.

3. In an accordian including bellows, a cell block comprising a plurality of cells one adjacent the other and each the full width of the cell block, a reed plate carrying a single free reed within each cell, an individual frame member removably sealed in one side of each cell carrying a pair of air intake valves, and another individual frame member removably sealed in the opposite side of each cell carrying a pair of air escape valves, so constructed and arranged whereby when the bellows are expanded air is drawn into a cell through one of the intake valves and in vibrating the free reed escapes from the cell into the bellows through one of the escape valves, and when the bellows are compressed air is forced into the cell through the other of the intake valves and in vibrating the free reed escapes from the cell through the other of the escape valves, a base frame member spanning the end walls and including a series of openings registering with each cell of the block, a cover common to the several openings of the top frame member, and latching means removably securing the cover over the top frame member.

4. In an accordian including bellows, a cell

block comprising a plurality of cells one adjacent the other and each the full width of the cell block, a reed plate carrying a single free reed within each cell, an individual frame member removably sealed in one side of each cell carrying a pair of air intake valves, and another individual frame member removably sealed in the opposite side of each cell carrying a pair of air escape valves, so constructed and arranged whereby when the bellows are expanded air is drawn into a cell through one of the intake valves and in vibrating the free reed escapes from the cell into the bellows through one of the escape valves, and when the bellows are compressed air is forced into the cell through the other of the intake valves and in vibrating the free reed escapes from the cell through the other of the escape valves, a base frame member including a series of openings each in communication with a cell of the block, a pair of end walls mounted upon the base frame member, a top frame member spanning the end walls and including a series of openings communicating with each cell of the block, a cover common to the several openings of the top frame member, and latching means removably securing the cover to the end walls, the base member including means adapted for receiving the block in the end frame of the accordian.
